(57) CLAIM

The ornamental design for a barber clipper bag, as shown and described.

DESCRIPTION

FIG. 1 is a perspective view of a barber clipper bag, on a reduced scale, showing my new design;

FIG. 2 is a plan view of the interior, on an enlarged scale, thereof;

FIG. 3 is a top plan view thereof;

FIG. 4 is a left side elevational view thereof;

FIG. 5 is a front elevational view thereof;

FIG. 6 is a right side elevational view thereof;

FIG. 7 is a bottom plan view thereof;

FIG. 8 is a rear elevational view thereof; and,

FIG. 9 is a perspective view in the open position, on an enlarged scale, thereof.

The broken line showing of strap mounts and a handle in the views is for illustrative purposes only and forms no part of the claimed design.
